UNITED STATES PATENT OFFICE.

RALPH C. STROUT, OF WOLLASTON, MASSACHUSETTS, ASSIGNOR TO PNEUMATIC SCALE CORPORATION, LIMITED, OF NORFOLK DOWNS, MASSACHUSETTS, A CORPORATION OF MASSACHUSETTS.

PACKAGE-CONVEYING MECHANISM.

Application filed February 18, 1922. Serial No. 537,622.

To all whom it may concern:

Be it known that I, RALPH C. STROUT, a citizen of the United States, residing at Wollaston, county of Norfolk, Commonwealth of Massachusetts, have invented certain new and useful Improvements in Package-Conveying Mechanism, of which the following is a specification.

This invention relates to package conveying mechanism for packaging machinery, and particularly to a safety device for the package conveyor, whereby the excess packages on the conveyor will be removed if for any reason the conveyor becomes overfilled.

For the purposes of this application, I shall discuss my invention in the particular adaptation in which it has been found most suitable, namely, to the conveyor which operates between the bottom sealer machine and the weighing machine of a packaging system. It will be understood, of course, that this treatment is purely for purposes of illustration and in no way limiting.

Such conveyor occasionally becomes overfilled with packages, due to variation in the handling speeds of the bottom sealer and weigher, thereby choking the packaging system. Heretofore when such a condition occurs, it has been the usual practice to stop one of the machines, generally the bottom sealer, until the weigher shall have caught up with the package supply.

To the end therefore of rectifying this condition automatically and substantially at the moment that it occurs, and in an arrangement which will avoid the necessity of stopping either the bottom sealer or the weighing machine, I have devised my present invention.

According to my invention, I automatically remove from the belt the excess package or packages, as soon as the number of packages on the belt exceeds the normal number. The surplus packages thus removed may afterwards be replaced on the belt and fed through the system, but at the time of removal, they are definitely taken out of the working range of the system so as to avoid all possibility of interference therewith. The mechanism for carrying out the principles of my invention is simple in

construction, and is characterized by the positive and immediate response of the parts whenever the number of packages on the belt exceeds the normal number.

So long as the number of packages on the belt is normal, the package remover is inactive, but whenever the number of packages on the belt exceeds the normal number, the surplus packages themselves automatically cause the package remover to come into operation and successively remove packages from the belt until such time as the number of packages on the belt is restored to normal, whereupon the pusher is again thrown out of operation.

The construction and operation of my invention, together with an embodiment thereof of which not only well illustrates the principles involved, but is itself an organized structure which has been found satisfactory in actual use, is described and shown in the accompanying specification and drawings, and the characteristic features of novelty are particularly pointed out in the appended claims. Throughout the specification and drawings like reference characters are correspondingly applied, and in the drawings:

Fig. 1 is a side elevation of a conveyor in accordance with my invention.

Fig. 2 is a plan view thereof, with the belt partially broken away, to expose the underlying mechanism.

Fig. 3 is an end view thereof, and showing the package pusher in its normal inoperative position.

Fig. 4 is a fragmentary plan detail showing the package feeler swinging freely across the belt, as happens when the number of packages on the belt is normal.

Fig. 4^a is a transverse section corresponding to Fig. 4.

Fig. 4^b is a diagrammatic plan view corresponding to Figs. 4 and 4^a and showing the normal spacement of the packages on the belt.

Fig. 5 is a view similar to Fig. 4^b and showing the action of the pusher and feeler when there is an excess number of packages on the belt.

Figs. 5^a and 5^b are views similar to Figs.

4^a and illustrating respectively the obstruction of the feeler by a surplus package on the belt, and the operation of the pusher to remove a package from the belt, as indicated in Fig. 5, and

Fig. 6 is a detail section along the cam shaft of the device.

According to my invention I provide a package detector or feeler which, when the number of packages on the belt is normal intermittently swings freely between the packages but which, when there is an excess number of packages on the belt, is obstructed by a package and immediately sets into operation a normally inactive package pusher disposed in the rear thereof and effective when actuated to successively remove the packages from the belt until such time as the number of packages on the belt has been restored to normal, whereupon the pusher is automatically thrown out of operation, and the feeler resumes its normal action.

I have indicated at 1 the package receiving belt of a conveyor of standard type, at 2 the frame rails thereof, and at 3 the package guide rails which extend longitudinally above the upper flight of the belt on either side thereof, and are opened between their ends, as indicated at 6, Fig. 1, to permit the pusher to swing across the belt and eject a surplus package therefrom.

The belt 1 may operate between any two points between which it is desired to transfer articles, and in the adaptation selected as illustrative of the principles of my invention, said belt operates between a bottom sealer machine which would be disposed at the left in Fig. 1 and a package weighing machine which would be disposed at the right in Fig. 1, the packages delivering from the bottom sealer onto the belt 1 and being transferred by said belt to the weighing machine.

Movable intermittently across the belt in properly timed relation to the feed of the packages is a package detector or feeler 4 which controls the operation of an excess package remover or pusher 5. The pusher 5 is normally inactive so long as the number of packages on the belt is normal and the feeler swings freely across the belt, but is automatically set into operation to swing transversely across the belt in rear of the feeler 4 when the motion of the feeler is checked by a surplus package on the belt whereby to push the package next following such obstructing package laterally off the belt through the gap 6 in the guide rail 3.

The feeler 4 may be given intermittent motion across the belt in a variety of ways and the feeler itself may be constructed in a variety of forms. As here shown, said feeler is disposed as a finger adjustably

mounted at 7 on an arm 8 which is fast to a rock shaft 9 journaled in suitable bearings 11 depending from the frame rails 2, Figs. 1 and 2.

The rock shaft 9 is actuated through an arm 10 thereon which is provided with a roll 12 operating on the face of a ratchet-carrying cam 13 which is fast on a cam shaft 14, journaled in suitable bearings 15 depending from the frame rails 2.

The shaft 14 is continuously driven in any suitable manner, and in the embodiment selected as illustrative herein, is driven from the sealing machine by a sprocket 16 on said shaft 14 which is connected by a sprocket chain 17 with a sprocket 18 on a shaft 19 driven from the sealer.

The cam 13 has a pocket 20 into which the roll 12 drops to cause the feeler to swing across the belt, Figs. 4^a and 4^b, between the packages thereon. So long as said roll is out of said pocket, Fig. 5^a, the feeler is retracted clear of the belt to permit a package to feed therewith.

The operation of the feeler finger 4 is so timed relative to the delivery of packages to the belt 1 that when the number of packages on the belt is normal, the feeler will pass across the belt between the packages, Fig. 4^b, at a time when there is no package in position on the belt to obstruct the movement of said finger. So long as this condition continues, the operation of the feeler finger is idle and ineffective upon the package pusher 5, which therefore remains in the inoperative position shown in Fig. 2 in which position it is clear of the belt. When, however, there is an excess number of packages upon the belt, due either to an excess delivery of packages or to a difference in the handling speeds of the bottom sealer and weigher or to any other cause, and the belt fills up with packages, the inward movement of the feeler finger 4 across the belt will be checked by the presence of a package in the path of said finger, Figs. 5 and 5^a.

When this condition occurs, the pusher is promptly and automatically set into motion and swings through the nearer gap of the registering pair of gaps 6 in the guide rails 3 to push a package off the belt through the opposite gap. The pusher continues to operate until the number of packages on the belt is restored to the normal number, at which time, the feeler finger will again swing freely between the packages and the package pusher will be thrown out of operation.

The mechanism for setting the pusher into operation when the feeler 4 is checked may be constructed in a variety of ways, and as here shown, the pusher 5 is set into operation by the rocker arm 21 to which it is connected and which arm is loose on the rock

shaft 9 and has a roll 22 thereon adapted to operate against the cam face 23 of a combination double cam and pawl carrier 24 which is mounted loosely on the shaft 14 so as normally not to rotate therewith.

Pivoted at 25 to the cam 23 of the two part cam 24 is a pivoted pawl 26, the toe of which is normally urged downwardly towards the teeth 27 of a ratchet 28 fast on the cam 13 in slots 29 therein by a slight blade spring 30, Fig. 5^a, which is anchored at 31 and at its free end bears upon the toe of the pawl. The rise of the pawl is limited by a stop 41 on the cam 23.

15 The ratchet teeth extend as a short series about the periphery of the ratchet 28 and the pawl is normally held disengaged from said teeth by a pawl stop arm 32 fast on the rock shaft 9 between the cams 13 and 23.

20 Coiled about the rock shaft 9 between the arm 8 and the adjacent bearing 10 in a torsion spring 33, the normal tendency of which is to throw the pawl stop 32 inwardly towards the pawl, as the shaft 9 is rocked by 25 the cam 13 and arm 11.

At each revolution of the cam shaft 14 therefore, the pawl stop 32 is rocked down against the heel of the pawl 26 to lift the toe thereof away from the ratchet 28 so as 30 to prevent the cam 24 from being clutched to the shaft 14 to rotate therewith.

Anchored at 34 to one of the frame rails 2 is a tension spring 35 which is connected at 36 to an extension 37 of the pusher arm 35 21 and normally tends to throw the pusher inwardly.

40 Loose on the rock shaft 9 is an arm 38 which is provided with a roll 39 adapted to work against the face 40 of the combination double cam and pawl carrier 24 when said cam is clutched to the cam 13 to rotate therewith. Anchored to said arm 38 and to one of the frame rails 2 is a tension spring 39', the normal tendency of which is to hold 45 the arm in the position of Fig. 3 wherein it will assist to prevent accidental rotation of the cam 24 and pawl 26 relative to the cam 13 and ratchet 28.

The rotation of the cam shaft 14 is transmitted to the rock shaft 9 by the rocker arm 11, cam roll 12, and cam 13 fast on the cam shaft whereby to rock said shaft 9 to swing the feeler 4 across the belt between the packages P, P' and P² thereon Figs. 4^a 55 and 4^b, when the package number is normal, and to swing the pawl stop 32 down against the heel of the pawl 26 to lift the pawl away from the ratchet and prevent the cam 24 from being clutched to the cam shaft 14 to 60 rotate therewith. This is the normal operation of the parts so long as the number of packages on the belt is normal, and inasmuch as no rotation is imparted to the cam 24, the pusher 5 is not actuated and remains 65 in its ineffective position shown in Figs. 3

and 4^b. When, however, there is an excess number of packages on the belt, the feeler 4 is stopped in its motion across the belt by the presence of a package P in obstructing position thereon, Figs. 5, 5^a and 5^b, and the package pusher 5 thereupon is brought into operation to remove the package P' next in the rear of the obstructing package.

70 This is accomplished as follows:

When the movement of the feeler 4 across the belt is interrupted by an obstructing package P thereon, the pawl stop 32 is prevented from engaging and lifting the pawl clear of the ratchet teeth and the cam 24 which carries said pawl is thereby coupled with the cam 13 which carries the ratchet so as to rotate therewith. The rotation of the cam 24 through the cam face 23, roll 22, and rocker arm 21 swings the pusher 5 inwardly across the belt to push therefrom the package P' next in the rear of the obstructing package P (Fig. 5). The same rotation of the cam 24 through the cam face 40 thereof, roll 39, and rocker arm 38 rocks the arm 38 to overcome the spring 39' and permit 80 the cam 24 and with it the pawl 26 to rotate freely with the cam 13 and ratchet 28. The pusher 5 continues to operate until the number of packages on the belt is again restored to normal, whereupon the feeler 4 will 85 again swing freely across the belt between the packages and the pawl stop 32 will again intermittently engage and lift the pawl clear of the ratchet so as to prevent rotation of the cam 24 and consequent actuation of the 90 pusher.

Various modifications in the form and construction of my invention may obviously be restored to without departing from the spirit of the invention if within the limits 105 of the appended claims.

What I therefore claim and desire to secure by Letters Patent is:

1. In combination with a way along which packages travel, a normally ineffective package remover for automatically removing surplus packages from said way, and means operated by the presence of a surplus package on said way for automatically setting said package remover into operation.

2. In combination with a way along which packages travel, a normally ineffective package remover for automatically removing surplus packages from said way, and means disposed adjacent said package remover and operated by contact with a surplus package on said way for automatically setting said package remover into operation.

3. In combination with a way along which packages travel, a normally ineffective package remover for automatically removing surplus packages from said way, and a detector disposed adjacent said package remover for normal intermittent travel between the packages on said way and operated by contact 130

with an obstructing package on said way for automatically setting said package remover into operation.

4. In combination with a way along which packages are adapted to travel, a normally ineffective package remover automatically set into operation by the presence of a surplus package on said way.

5. In combination with a way along which packages travel, a package detector normally movable intermittently across said way between the packages thereon when the package number is normal, and a normally ineffective package remover controlled by said detector and automatically set into operation by the presence of an excess number of packages on said way.

6. In combination with a way along which packages travel, a package detector normally movable intermittently across said way between the packages thereon when the package number is normal and a normally ineffective package remover automatically set into operation whenever the free movement of said detector across said way is obstructed by the presence of a surplus package on said way.

7. In combination with a way along which packages travel, a package detector normally movable intermittently across said way between the packages thereon when the package number is normal, a normally ineffective package pusher disposed adjacent said detector and automatically set into operation whenever the free movement of said detector across said way is obstructed by the presence of a surplus package on said way, and operative connections between said detector and pusher normally permitting movement of said detector and preventing movement of said pusher and effective upon contact of said detector with an obstructing package on said way to permit movement of said package pusher.

8. In combination with a way along which packages travel, spaced package guide rails adjacent said way, said rails having a pair of aligned gaps constituting respectively an entrance opening for a package pusher and a discharge opening for a package engaged by said pusher, a package detector normally movable intermittently across said way between the packages thereon when the package number is normal, and a normally ineffective package pusher automatically movable through said entrance opening of the guide rails whenever the free movement of said detector across said way is obstructed by the presence of a surplus package on said way to eject a package from said way through said package discharge opening of the guide rails.

9. In combination with a way along which packages travel, a drive shaft, a rock shaft operated therefrom, a package detec-

tor mounted on said rock shaft to normally move intermittently across the package way between the packages thereon, a normally ineffective package pusher, and pusher actuating mechanism automatically connected 70 to said drive shaft whenever the free movement of said detector across the package way is obstructed by the presence of a surplus package on said way whereby to cause said pusher to travel across the package way 75 and remove a package therefrom.

10. In combination with a way along which packages travel, a cam shaft, a rock shaft driven therefrom, a package detector fast on said rock shaft to normally move intermittently across the package way between the packages on said way, a normally ineffective package pusher on said rock shaft, and means automatically clutched to said cam shaft whenever the free movement of 85 said detector across the package way is obstructed by the presence of a surplus package on said way whereby to cause said pusher to travel across the package way and remove a package therefrom. 90

11. In combination with a way along which packages travel, a cam shaft, a rock shaft driven therefrom, a package detector fast on said rock shaft to normally move intermittently across the package way between 95 the packages on said way, a normally ineffective package pusher on said rock shaft, and means automatically clutched to said cam shaft, whenever the free movement of said detector across the package way is obstructed by the presence of a surplus package on said way whereby to cause said pusher to travel across the package way and remove a package therefrom. 100

12. In combination with a way along 105 which packages travel, a cam shaft, a rock shaft driven therefrom, a package detector fast on said rock shaft to normally move intermittently across the package way between the packages on said way, a normally ineffective package pusher on said rock shaft, a pusher operating cam loose on said cam shaft, and means effective whenever the free movement of said detector across the package way is obstructed by the presence of a 110 surplus package on to said way to clutch said pusher operating cam to the cam shaft whereby to cause said pusher to travel across the package way and remove a package therefrom. 115

13. In combination with a way along which packages travel, a cam shaft, a package detector operated therefrom to normally move intermittently across the package way between the package thereon, a pusher, a pusher operating cam loose on said cam shaft, a pawl carried by said cam, a ratchet fast on said cam shaft, and a pawl trip operated during the movement of the package detector and normally effective to prevent 125 120 125 130

- engagement of said pawl and ratchet and effective whenever the free movement of said detector across said way is obstructed by the presence of a surplus package on said way to permit said pawl to engage said ratchet and couple said pawl-carrying cam to said cam shaft whereby to cause the package pusher to travel across the package way and remove a package.
14. In combination with a way along which packages travel, a cam shaft, a rock shaft driven therefrom, a package detector mounted on said rock shaft to normally move intermittently across the package way between the packages thereon, a pusher, a pusher operating cam loose on said cam shaft, a pawl carried by said cam, a ratchet fast on said cam shaft, and a pawl trip mounted on said rock shaft and normally effective to prevent engagement of said pawl and ratchet and effective whenever the free movement of said detector across said way is obstructed by the presence of a surplus package on said way to permit said pawl to engage said ratchet and couple said pawl-carrying cam to said cam shaft whereby to cause the package pusher to travel across the package way and remove a package therefrom.
15. In combination with a way along which packages travel, a cam shaft, a rock shaft driven therefrom, a package detector mounted on said rock shaft to normally move intermittently across the package way between the packages thereon, a pusher, a pusher operating cam loose on said cam shaft, a pawl carried by said cam, a ratchet fast on said cam shaft, a spring normally urging said pawl towards said ratchet, and a pawl trip mounted on said rock shaft and normally effective to intermittently engage and lift the pawl away from the ratchet and effective whenever the free movement of said detector across said way is obstructed by the presence of a surplus package on said way to permit said pawl to engage said ratchet and couple said pawl-carrying cam to said cam shaft whereby to cause the package pusher to travel across the package way and remove a package therefrom.
16. In combination with a way along which packages travel, a cam shaft, a cam fast thereon, a rock shaft driven by said cam, a package detector mounted on said rock shaft to normally move intermittently across the package way between the packages thereon, a pusher, a pusher operating cam loose on said cam shaft, a pawl carried by said pusher operating cam, a ratchet fast on said rock shaft operating cam, and a pawl trip mounted on said rock shaft and normally effective to intermittently engage and lift the pawl away from the ratchet and effective whenever the free movement of said detector across said way is obstructed by the presence of a surplus package on said way to permit said pawl to engage said ratchet and couple said pawl-carrying cam to said cam shaft whereby to cause the package pusher to travel across the package way and remove a package therefrom.
17. In combination with a way along which packages travel, a cam shaft, a cam fast thereon, a rock shaft driven by said cam, a package detector mounted on said rock shaft to normally move intermittently across the package way between the packages thereon, a pusher, a pusher operating cam loose on said cam shaft, a pawl carried by said pusher operating cam, a ratchet fast on said rock shaft operating cam, a pawl trip mounted on said rock shaft and normally effective to intermittently engage and lift the pawl away from the ratchet and effective whenever the free movement of said detector across said way is obstructed by the presence of a surplus package on said way to permit said pawl to engage said ratchet and couple said pawl-carrying cam to said ratchet carrying cam whereby to cause the package pusher to travel across the package way and remove a package therefrom, a spring tensioned detent on said rock shaft having a normal restraining relation to said pawl carrying cam to prevent rotation thereof with said cam shaft and a roll on said detent engaged by said pawl carrying cam to remove said detent when said cam is coupled to said cam shaft to rotate therewith.
18. In combination with a conveyor along which packages are adapted to travel, a pair of spaced guide rails disposed adjacent the upper flight of the conveyor and interrupted between their ends to provide aligned pusher entrance and package discharge openings, a cam fast on said cam shaft, a rock shaft operated by said cam, a package detector mounted on said rock shaft and normally movable intermittently across the conveyor between the packages thereon, a package pusher mounted on said rock shaft adjacent said detector and normally disposed in inoperative position, a cam loose on said cam shaft for actuating said package pusher, a pawl carried by said pusher actuating cam, a ratchet carried by said rock shaft actuating cam, a pawl stop fast on said rock shaft and normally effective to hold said pawl out of engagement with said ratchet and ineffective upon interruption of the movement of said detector by the obstruction of a surplus package on the conveyor to hold said pawl and ratchet mechanism disengaged whereby the pusher actuating cam is clutched to the cam shaft to rotate therewith and swing the pusher across the belt through the pusher entrance opening of the guide rails to eject a package

6
therefrom through the discharge opening of said rails.

19. The combination with a way adapted to receive a definite number of spaced traveling packages, of a movable package engaging device having a normal timed entry into the package path coincident with the normal spaces between the packages but effective if its entry be blocked by the presence of a surplus package on said way to cause the removal of a package from said way.

20. The combination with a way along which a definite number of packages are adapted to travel to a point of delivery, of a package engaging device effective adjacent to the point of delivery upon the accumulation of a predetermined number of packages at the point of delivery to cause removal of any surplus package from said way.

21. In combination with a way along which a definite number of packages are

adapted to travel in successive spaced relation, a package detector having a normal 25 timed entry into the package path coincident with the normal spaces between the packages, and means controlled by the detector if its entry be blocked to remove any surplus package from said way. 30

22. In combination with a way along which a definite number of packages are adapted to travel to a point of delivery, a package detector adjacent the point of delivery, and a package arrestor operable by 35 said detector upon the accumulation of a predetermined number of packages at the point of delivery to remove any surplus package from said way.

In testimony whereof I affix my signature 40 in presence of two witnesses.

RALPH C. STROUT.
